US0D1033822S

(12) **United States Design Patent** (10) **Patent No.:** **US D1,033,822 S**
(45) **Date of Patent:** **** Jul. 9, 2024**

(54) **SOLE**

(71) Applicant: **adidas AG**, Herzogenaurach (DE)

(72) Inventors: **Stanislas Goussev**, Nuremberg (DE);
Carl Arnese, Portland, OR (US); **Felix Braun**, Nuremberg (DE)

(73) Assignee: **adidas AG**, Herzogenaurach (DE)

(**) Term: **15 Years**

(21) Appl. No.: **29/786,126**

(22) Filed: **May 28, 2021**

Related U.S. Application Data

(63) Continuation of application No. 29/703,580, filed on Aug. 28, 2019, now Pat. No. Des. 922,045, which is a continuation of application No. 29/590,094, filed on Jan. 6, 2017, now Pat. No. Des. 862,051.

(30) **Foreign Application Priority Data**
